UNITED STATES PATENT OFFICE

JAY GOULD COUTANT, OF NEW YORK, N. Y., ASSIGNOR TO FURNACE ENGINEERING COMPANY, INC., OF NEW YORK, N. Y., A CORPORATION OF NEW YORK

FURNACE

Application filed February 23, 1929. Serial No. 342,039.

This invention relates to furnaces, its chief utility being in respect to furnaces for heating steam boilers, and particularly furnaces fired with pulverized coal or similar fuel. The general objects of the present invention include the general improvement in the efficiency of firing of furnaces, while increasing the thoroughness of combustion, rate of evaporation and the durability and economy of operation of the furnace. Further objects and advantages of the present invention will be explained in the hereinafter following description of illustrative embodiments thereof or will be apparent to those conver-

sant with the subject. To the attainment of such objects and advantages the present invention consists in the novel furnace and the novel features of operation, combination, arrangement and construction herein illustrated or described.

In the accompanying drawing Fig. 1 is a partial elevation and vertical section of a boiler furnace embodying the present invention.

Figs. 2 and 3 are detail section views either of which may be considered as taken on the line $\alpha-\alpha$ of Fig. 1, showing the relation, in the water arch, of the tubes and the closing wall members.

Figs. 4 to 7 are corresponding cross sections showing four other different structural modifications.

This application is claimed to be a continuation in part of my prior application filed March 5, 1925, upon which patent is about to issue on February 26, 1929, No. 1,703,814, and of my copending applications Serial No. 60,435, filed October 5, 1925 and Serial No. 176,137, filed March 17, 1927.

In the prior patent the fuel is shown in Fig. 4 as being introduced at the left side of the chamber beneath a water cooled arch. The fuel is in the form of pulverized coal in suspension in air, forming a flame directed into the combustion chamber, this flame entering the chamber between cooling surfaces both above and below, namely the water arch above and a water cooled floor or bottom below. Figs. 2 to 7 hereof correspond substantially with Figs. 10 to 14 of the prior

patent. The form of burner or pulverized fuel injector as herein shown does not correspond with the form shown in the prior patent, but corresponds with that shown in another prior application of mine, although either burner, or other burner could be employed in the same relation.

The furnace is a boiler furnace and is shown as enclosed between a front wall 10 and side walls 11, and an opposite rear or bridge wall will be understood. The side walls are of a type having water cooling tubes 12 in the upper part of the chamber for progressive cooling of the gases ascending toward the boiler. Below is the water bottom or floor 13 shown as comprising water circulation tubes 14 for the cooling of the floor. As in the prior patent the water bottom is inclined and is provided with jets 15 for driving settled ashes downwardly into the ash discharge opening 16 leading to an ash chamber or pit.

In the front wall 10 is shown a burner 18 which may be considered as representative of a series of burners arranged along one or more walls. The burner may be of various types, but is shown of a type described in a prior application wherein are a system of tubes 19 bringing the pulverized coal in suspension in air for delivery laterally into the burner and a nozzle 20 at the outer end for delivering forced draft air longitudinally into the burner. The combustion starts with in the chamber 21 of the burner and the flame is delivered at the mouth or delivery point 22 laterally into the combustion chamber of the furnace.

Above the combustion chamber is shown a water tube boiler 24 having baffles 25 of a usual sort. Between these and the front wall 10 is shown an arch 26 and for the purposes of this invention this arch, which is arranged the fuel admission point, and exposed to the radiant heat, is provided with water circulation passages or tubes 27 arranged for high heat absorption. It will be noted that the arch 26 is slanted upwardly away from the wall through which the fuel is admitted and the bottom 13 is slanted downwardly away from the same wall, so that in effect the fuel

is injected into the water cooled flaring side or extension of the general combustion chamber.

The water tubes 27 of the arch are shown 5 as supplied with water by a downtake pipe 28 leading from the boiler to the lower header 29, the water passing thence through the system of arch tubes 27 and from them into the upper header 30. From this upper header 10 preferably take-off a system of widely spaced tubes 30^a forming a slag screen substantially below the point where the combustion chamber narrows in entering the boiler.

The particular construction of the arch as 15 shown in Fig. 1 is further shown in Fig. 2 or 3. A system of blocks 31 is arranged with flanges 32 extending down into partial shielding position between the tubes 27. In Fig. 3 similar blocks 31^a have depending flanges 32^a between the tubes. An outer refractory layer 33 is shown, which of course may also be employed in Fig. 2 or 4.

The blocks 31 and 31^a and their depending flanges are preferably composed of firebrick refractory. Thus the radiant heat is directed 20 toward the tubes 27 and toward the refractory flanges. The flanges protect the tubes from excessive heating and destruction. The flanges also prevent excessive absorption of 25 radiant heat and thus maintain a suitably high flame temperature at the delivery of the burner. The circulation tubes in turn protect the refractory elements and preserve the arch from destruction, while greatly enhancing the total evaporation, and preventing the ill effects of excessively high flame 30 temperatures.

Fig. 4 is similar to Fig. 3, but with the depending flanges of the blocks 35 cut off to 40 expose the tubes substantially to their diameters.

In any of these constructions, the interposed blocks might in some cases be constructed partly or wholly of metal, or the 45 tubes might be faced with metal, or other high heat conducting material, but as stated the preferred arch presents a combined surface of refractory material and water cooled tubes to the radiant heat.

In Fig. 5 the depending blocks 36 may be 50 composed of metal and give dove-tail support to silicon carbide blocks 37, representative of any high heat conducting refractory block. In this case the blocks are arranged substantially to cover and protect the tubes, but to deliver effectively the absorbed heat to the 55 circulating medium. The block 36 is shown supported from a backing 38.

In Fig. 6 the blocks 40 are of metal, but 60 otherwise similar to the blocks 37 in Fig. 5. The blocks 40 are secured by a clamping device 41 with a rear metal bar 42 below a backing 43. In Fig. 7 the construction is similar but the metal block 40 is provided with a 65 silicon carbide face insert 45.

The operation has been largely indicated. The burners deliver the flames laterally or horizontally into the general chamber. They sweep across the chamber and then swing up through the temperature reducing zone surrounded by the tubes 12, and thence between the tubes of the slag screen 30^a and into the boiler passes. With this invention the progressive cooling of the flames commences shortly beyond the exit of the burners due to the radiant heat absorbing surfaces or water arch and bottom above and below the flames. Complete combustion is assured by the high initial temperature while slagging is prevented by the progressive cooling below the melting point of the suspended ash, both as to ash rising toward the boiler and ash settling toward the bottom. Due to the combined arrangement of water tubes and refractory elements the water arch is strong and durable. It utilizes radiant heat to increase evaporation and cooperates in the combustion operations. In the case of injected fuel the water arch cooperates with the water bottom beneath as already described.

There has thus been described a furnace embodying the principles and attaining the advantages of the present invention, being illustratively shown as a boiler furnace burning pulverized coal. Since many matters of operation, combination, arrangement and construction may be variously modified without departing from the principles, the invention is not intended to be limited to such matters except to the extent set forth in the appended claims.

What is claimed is:

1. In a pulverized fuel boiler furnace having a combustion chamber in which the boiler is exposed, a burner admitting fuel and air in a lateral direction through a lateral wall of the chamber, an arch above the burner exposed to the radiant heat, a bottom wall below the burner exposed to the radiant heat, said arch and bottom being arranged to diverge in the direction of fuel admission, and water circulating tubes in both said arch and bottom, in circulation with the boiler.

2. In a boiler furnace having a combustion chamber, a burner admitting fuel through one of the lateral walls of the chamber, an arch thereabove exposed to the radiant heat, said arch having water circulation passages arranged for high heat absorption, a slag screen of spaced water tubes across the upper part of the furnace, and connections between the water circulation passages and the slag screen tubes so arranged that the circulation passages deliver to said slag screen.

3. A pulverized fuel boiler furnace comprising walls constituting a combustion chamber below the boiler, an arch, a water cooled bottom, a screen of widely spaced water tubes between the combustion zone and

boiler for chilling the ashes in the upgoing products, water tubes facing said arch and a connection from said tubes to the water tubes of the screen.

5 4. In a boiler furnace having a combustion chamber in which the boiler is exposed, means injecting pulverized fuel in suspension in air laterally into the combustion chamber through one of the lateral walls thereof, an arch above 10 said injecting means exposed to the radiant

heat, and having spaced water circulation tubes arranged for radiant heat absorption, said arch being inclined upwardly away from the fuel injection point, and a closed furnace bottom inclined downwardly away from the 70 fuel injection point and having water circulation passages for absorption of radiant heat.
